NOZZLE STRUCTURE FOR AIR DISTRIBUTING APPARATUS AND THE LIKE

John R. Andrews, Jr., Uxbridge, Mass., assignor to Bachmann Uxbridge Worsted Corporation, Uxbridge, Mass., a corporation of Massachusetts

Application December 7, 1951, Serial No. 260,446

5 Claims. (Cl. 98—40)

1

This invention relates to apparatus for delivering an attempered stream of air to and through a web, such for example as a warp sheet and the like. For convenience the apparatus will be referred to herein as a drier and in the embodiment of the invention shown in the drawings an important part of the invention is embodied in the nozzle structure of an air distributing header which is shown positioned within a drying box of the general kind disclosed in United States Patent No. 2,541,383, issued February 13, 1951, and my co-pending applications Serial No. 122,482, filed October 20, 1949, now Patent No. 2,601,080 and Serial No. 128,134, filed November 18, 1949.

An object of this invention is to provide a simple, compact apparatus of the above mentioned kind.

Another object of the invention is to provide improved, nozzle structure for delivering attempering air gently and uniformly to and through a web, such for example as a warp sheet and the like, without stretching, elongating, or otherwise distorting the threads, yarns, filaments etc. of which it is comprised.

Other objects of the invention will be in part obvious or in part pointed out hereinafter.

The invention accordingly consists in the features of construction, combinations of elements, arrangements of parts, and in the several steps and relation and order of each of said steps to one or more of the others thereof, all as will be pointed out in the following description, and the scope of the application of which will be indicated in the following claims.

The invention will best be understood if the following description is read in connection with the drawings, in which,

Figure 1 is a side elevation, partly in cross section, of an embodiment of the invention;

Figure 2 is a fragmentary view, also in side elevation, of a portion of the composite nozzle structure of the header shown in Figure 1; and

Figure 3 is a vertical cross sectional view taken on the line 3—3 of both Figures 1 and 2.

In the embodiment of the invention disclosed herein a closure 10 is provided into which a warp sheet W is introduced through port 12 in the rear wall, and from which the warp sheet is discharged through the air inlet port 14 in the front wall. An air outlet 15 with a suction fan 15a is provided near the top of the rear wall of closure 10 through which is discharged the increment of the air which has passed through the wettest portion of the warp sheet. Before enter-

2

ing into closure 10 the warp sheet passes through a sizing bath and rolls, indicated generally by the numeral 16.

Within closure 10 is provided an elongated single header 18 the upper surface of which comprises a series of composite nozzles, to be more fully described. Header 18 extends forwardly and upwardly from just below entrance port 12 toward the top of the front wall of closure 10. Two rollers 24 and 26 are provided in spaced relation longitudinally of the header near the front end of said header and a single roller 28 is provided adjacent the rear end of said header above port 12, and the warp sheet W is led from the sizing bath 16 through entrance port 12 through a long reach and around roller 24, in a path parallel and adjacent to the upper surface of the header, and then back to roller 28 through a second reach substantially parallel to said first reach, and around roller 28 and back to roller 26 through a third reach substantially parallel to said first and second reaches, and, after passing over roller 26 the warp sheet is led down to roller 30 adjacent the exit port of the chamber 10 and out through the said air inlet port 14.

In its first reach the warp sheet may be divided into a number of sheets as for example by the splitter rollers 32, 34 and 36, as shown for example in my co-pending applications Serial No. 122,482, filed October 20, 1949, and Serial No. 128,134, filed November 18, 1949.

Within closure 10, adjacent to and in horizontal alignment with closure port 14, are the heaters 38 through which the incoming air and an increment of the used air is passed into chamber 40 which communicates with chamber 42 through the vanes or dampers 43 by which the volume of air supplied to chamber 42 may be controlled. Chamber 42 houses air impeller or fan means 44 and has the discharge port 46 communicating with said single header 18. The air from chamber 42 is distributed within said header by means of baffles 48 and discharged from said header through said composite nozzles which are disposed along the upper surface of header 18, and extend laterally throughout substantially the full width of the header, as shown in Figure 3. The ports comprising the nozzles are made small enough to insure that the air supplied to the header will fill the header and issue in many equally spaced streams of substantially equal volume.

The nozzle structure comprises two series of inwardly opening trough-like members 52 and 54, disposed in spaced but parallel lines compris-

ing a surface, the top surface as shown herein, of an air distributing apparatus such as header 18. The trough-like members 52 of the first or inner series are spaced apart forming ports or channels 56 between successive members. Each member 52 comprises the side walls 52^a and 52^c and the end wall 52^b extending between the outer ends of said side walls, leaving the member open inwardly. Thus each port or channel 56 is defined by the side wall 52^c of one member 52 and the side wall 52^a of the member 52 nearest to said side wall 52^c.

The members 54 of said second series are similar to members 52 of the first series and they are spaced apart forming the ports or channels 58 between successive members 54. Each member 54 comprises the side walls 54^a and 54^c and end wall 54^b extending between the outer ends of said side walls. Each port or channel 58 is defined by the side wall 54^c of one member 54 and the side wall 54^a of the member 54 nearest to said side wall 54^c, leaving the member open inwardly. The members 54, however, are offset with respect to members 52 and respectively bridge the channels 56 between successive members 52.

The members 52 are supported at their ends by the side rails or flanges 60 and 62 extending longitudinally along the inner surface of the respective side walls 20 and 22 of the header. The side rails or flanges 60 and 62 may be welded to the header side walls 20 and 22 respectively or supported at their ends so that they are readily removable and the members 52 may be bolted to said flanges as by bolts *b*. The members 54 are similarly supported on the side rails or flanges 64 and 66 extending longitudinally along the inner surface of the side walls respectively of the header, and outwardly of flanges 60 and 62. The whole assembly comprising supporting members 60—66 and the members 52 and 54 rest on the angle members 68 and 70 projecting inwardly from the header side walls 20 and 22 respectively, and secured thereto by bolts *b*.

Air supplied into the header will be retarded and distributed by the members 52. Air attempting to enter said members 52 will encounter an air cushion of relatively dead, unmoving air, and, after being slowed down, will be diverted through said channels 56. The air streams issuing from channels 56 will similarly be slowed down by encountering cushions of relatively dead or unmoving air within members 54, causing said air streams to be slowed down and each stream deflected, and divided into two streams flowing around opposite ends of a member 54 and through the channels 58 which are at the opposite ends of said member 54.

It will be seen that part of the air streams from two channels 56 will issue through a single channel 58. Thus as shown in Figure 2 an increment *x* of the air stream flowing through one channel 56 will be deflected toward an increment of air *y* flowing through the adjacent channel 56, and the air streams *x* and *y* will be caused to flow toward one another, after being diverted by the members 54 bridging said channels 56 respectively, and will thus oppose one another and slow each other further before flowing outwardly together through the channel 58.

I have found that an unexpectedly gentle and even flow of air may be obtained by this nozzle structure which also has the advantages of simplicity and ease of assembly.

It will thus be seen that there has been provided by this invention an apparatus in which

the various objects hereinabove set forth together with many thoroughly practical advantages are successfully achieved. As various possible embodiments might be made of the mechanical features of the above invention and as the art herein described might be varied in various parts, all without departing from the scope of the invention, it is to be understood that all matter hereinbefore set forth or shown in the accompanying drawing is to be interpreted as illustrative and not in a limiting sense.

What I claim is:

1. The nozzle structure comprising a header having along one surface of a series of trough-like members each opening inwardly and comprising two parallel side walls and an outer wall, said members being spaced apart forming channels between the adjacent side walls of adjacent members, and a second series of inwardly opening trough-like members positioned outwardly from said first series and spaced apart forming channels between adjacent members, and offset with respect to said first series causing the members of said second series to bridge the ports respectively of said first series, whereby air flow within said header is retarded by members of said first series and directed between the members of the first series, and the flow of the air through the ports of said first series is retarded by the members of the second series and deflected to pass through the channels of said second series.

2. A nozzle structure comprising a header having along one surface a series of trough-like members each opening inwardly and comprising two parallel side walls and an outer wall, said members being spaced apart forming ports between the adjacent side walls of adjacent members, and a second series of inwardly opening trough-like members positioned outwardly from said first series and spaced apart forming ports between adjacent members, and offset with respect to said first series causing the members of said second series to bridge the ports respectively of said first series, whereby air flow within said header is retarded by the members of said first series and directed between the members of the first series, and the flow of the air through the ports of said first series is retarded by the members of the second series and deflected to pass through the ports of said second series, the members of said second series each acting to divide the stream of air from one port of said first series and divert it through two ports of said second series.

3. The nozzle structure comprising a header having along one surface a series of trough-like members each opening inwardly and comprising two parallel side walls and an outer wall, said members being spaced apart forming ports between the adjacent side walls of adjacent members, and a second series of inwardly opening trough-like members positioned outwardly from said first series and spaced apart forming ports between adjacent members, and offset with respect to said first series causing the members of said second series to bridge the ports respectively of said first series, whereby air flow within said header is retarded by the members of said first series and directed between the members of the first series, and the flow of the air through the ports of said first series is retarded by the members of the second series and deflected to pass through the ports of said second series, a portion of the air flowing through two successive ports of said first series being brought together

for passage through a single port of said second series, the increments of air from the said two ports of said first series being deflected toward one another before passage through said port of said second series and thus each exerting an impeding and slowing action one on the other. 5

4. A nozzle comprising two trough-like members opening inwardly and spaced apart forming a port between them, and a third inwardly opening trough-like member positioned outwardly from said first two members and bridging the port between said first two members, whereby air from the port between said two members is divided by said third member and caused to flow in two streams around opposite sides of said third member. 10

5. An air distributing header having a discharge wall comprising a series of nozzles, each nozzle comprising five trough-like members disposed with their open ends facing inwardly of the 15

10

15

20

header three in one line and two in a second line spaced from and substantially parallel to said first line, said three members being spaced apart thus defining two channels, and said two members being spaced apart forming between them a channel and being offset with respect to said three members to bridge the channels respectively defined by said three members.
